UNITED STATES PATENT OFFICE.

ARTHUR BURDETTE SMITH, OF SOUTH BROWNSVILLE, PENNSYLVANIA.

PHONOGRAPH RECORD.

Application filed April 6, 1922. Serial No. 550,214.

To all whom it may concern:

Be it known that I, ARTHUR BURDETTE SMITH, a citizen of the United States, and a resident of South Brownsville, in the 5 county of Fayette and State of Pennsylvania, have invented new and useful Improvements in Phonograph Records, of which the following is a specification.

This invention relates to records for 10 reproducing machines such as phonographs and the like, and relates more particularly to records of the disk type.

An object of this invention is to produce 15 novel means whereby the trade marks and identifying indicia and titles of records of the disk type may be exhibited without necessitating the removal of the records from a cabinet or storage; and furthermore, an object of the invention is to produce a 20 record of the character indicated having greater capacity or record surface than those now commonly used.

It is a further object of this invention to 25 provide novel means whereby records now in common use may be provided with indicia by which their identity or character may be observed without the necessity of removing the records from a cabinet or storage; and the invention further contemplates the 30 provision of novel means by which the labels or tag-like tickets may be attached to the said records.

It is furthermore an object of this invention to provide identifying labels which 35 can be readily applied to records now in common use and which will prove comparatively inexpensive to manufacture.

With the foregoing and other objects 40 in view, the invention consists in the details of construction, and in the arrangement and combination of parts to be hereinafter more fully set forth and claimed.

In describing the invention in detail, reference will be had to the accompanying 45 drawings forming part of this application wherein like characters denote corresponding parts in the several views, and in which—

Figure 1 illustrates a plan view of an 50 improved record embodying the invention;

Figure 2 illustrates a plan view of a fragment of an ordinary record, showing a device embodying the invention applied thereto;

55 Figure 3 illustrates an end view of the tag holding clip;

Figure 4 illustrates a sectional view on the line 4—4 of Fig. 3;

Figure 5 illustrates a plan view of the blank from which the clip is formed; and 60

Figure 6 illustrates a plan view of a record of modified construction.

In these drawings 10 denotes a record which may be of any appropriate material, and it is here shown as having a plain 65 groove extending from its center to a point near the periphery. A record of this character will have increased capacity as compared with records now in common use that have a central field where the identifying 70 number and title are displayed. In the old types having this central field, it is necessary to remove the record before gaining a knowledge of the subject of the record. 75

In the embodiment of the invention shown in Fig. 1, the disk or record 10 has an extension or lip 11 on which the indicia is exhibited, and of course the inventor does not wish to be limited with respect to the surface ornamentation of this 80 part of the disk or record. Enough is illustrated in the drawing to demonstrate the utility of the invention and the manner, in which it is carried into practice. 85

In Fig. 2 a modification is illustrated, in which the record 12 is of the known type in which the central portion constitutes the field for exhibiting the indicia. In order to render it possible to identify the character 90 of the record by means external to or outside of the field of the record, a record holder is employed which is generally identified by the numeral 13.

In the present embodiment of the invention, the indicia or card holder is formed of a single piece of metal as shown in Fig. 5, and in producing this holder it will be seen that it can be made wholly by the stamping process, so that the cost of production will be comparatively small. 95

The section 14 of the holder is frame-like, in that it has an aperture 15 to expose the indicia on a card or indicia bearing element 16. The section has an extension 17 which 105 forms one of the jaws of a clip when the section 14 is bent or folded on the section 18, the said section 18 having an aperture 19 through which the indica may be seen. An extension 20 of the section 18 forms the 110 other member of the clip, and when the two sections are bent, one on the other, as shown

in Fig. 3, the extensions 17 and 20 are parallel and are adapted to be applied to opposite sides of the record for retaining the card holder in place.

- 5 The section 18 has flanges 21 and 22 which are adapted to be folded or bent around the edges of the section 14 to prevent the sections from spreading, one from the other, and to retain the jaws of the clip firmly in
 10 contact with the record to which they are applied. The section 18 is further provided with a flange or extension 22^a which is adapted to be bent around the edge of the section 14 after the card bearing the indicia
 15 has been inserted in the holder, in order to form a partial closure or guard to prevent the escape of the indicia bearing element, as it might escape due to centrifugal action while the record is being turned in the act
 20 of playing.

It follows from an inspection of this illustration that after the indicia bearing element has been applied and the clip or holder is attached to the record, it will have the
 25 appearance of the indicator shown in Fig. 2 and that it will be accessible without removing the record from the cabinet or storage.

In that form of the invention shown in

Fig. 6, the record 23 is substantially the 30 form shown in Fig. 1, in that the record groove extends from the center and terminates a distance from the periphery to form a marginal flange 24 which is substantially the same width as the extension 11 of 35 the record 10, and the whole surface of this marginal flange may be employed for advertising matter, or for the display of indicia, according to the wishes of the manufacturer. The embodiment shown in Fig. 6 40 is a modification of the invention as disclosed in Fig. 1 and is intended for use where economy of material is not an essential consideration in the manufacture or production of the record.

45 I claim:

1. In a record for phonographs, a circular record disk having a short integral marginal extension at one portion of its edge, and record-indicating indicia on the surface of said extension.
2. In a phonograph record, a relatively short laterally projecting tab formed integrally upon the edge thereof and adapted to have the name of the selection applied to 55 either face thereof.

ARTHUR BURDETTE SMITH.
